UNITED STATES PATENT OFFICE

OTTO CARTER BERRY AND HOWARD W. LINKERT, OF INDIANAPOLIS, INDIANA, AS
SIGNORS TO THE WHEELER-SCHEBLER CARBURETOR CO., OF INDIANAPOLIS,
INDIANA, A CORPORATION OF INDIANA

CARBURETOR

Application filed May 15, 1923. Serial No. 639,191.

This carburetor is an improvement on the carburetor invented by one of the present applicants, Otto Carter Berry, and described in his co-pending application Serial No. 635,013, filed April 27, 1923. It has the same general objects in view as the previous invention, with the exception that special emphasis has been put upon the following two points:

(1) As pointed out in the previous application, the air-valve of a carburetor of this type should not be allowed to flutter when the engine is pulling a heavy load at low speed. To prevent this a fuel dash-pot is used in these carburetors. When this dash-pot as heretofore constructed is sufficiently effective to damp out all fluttering, it tends to prevent a vigorous acceleration immediately after coasting, for the reason that it forces the air-valve to open so slowly. It is therefore one of the objects of this invention to obviate this difficulty.

(2) As is also pointed out in the previous application, when the throttle of a carburetor is suddenly opened wider, at least a portion of the gasoline will lag behind the air in its passage through the intake manifold of an engine, and this will result in a temporarily impoverished mixture at the engine cylinder, often being accompanied by a temporary lack of power or even by the stalling of the engine. This period of impoverishment is very short in its duration, however, and may be overcome by supplying a temporarily enriched mixture at the carburetor.

It is also true that during periods of deceleration the liquid fuel flows to the cylinders in amounts in excess of the requirements, tending to cause the engine to load. Supplying extra fuel too rapidly during acceleration or supplying it for too long a time will produce inferior results during acceleration, but will be especially bad in its effects when the acceleration is immediately followed by a deceleration. It is therefore the second object of this invention to obviate these difficulties by accurately adjusting the amount of extra gasoline to the requirements of the engine, both as to the rate of delivering it and the length of time during which it is delivered.

Further objects of this invention are as follows:

(3) To furnish a well atomized mixture of proper richness through a very wide range of rates of flow of the air through the carburetor.

(4) To furnish the engine with a lean and economical mixture when it is running at part throttle.

(5) To furnish the engine with such a mixture as to produce maximum power when the throttle is wide open.

(6) To provide a means that can be operated from the driver's seat to enrich the mixture throughout the range for starting and for gradually reducing the amount of such enrichment during the period of warming up.

The accompanying drawings illustrate our invention, and show a preferred embodiment thereof. In such drawings: Fig. 1 is a plan view of a carburetor embodying our invention; Fig. 2 is a vertical, longitudinal section thereof, taken on the line 2-2 of Fig. 1; Fig. 3 is a transverse vertical section on the line 3-3 of Fig. 1; Fig. 4 is a partial elevation, showing the control levers and adjustments; Fig. 5 shows the dash-pot piston in its normal position; Fig. 6 shows the action of this piston with a heavy suction suddenly applied to the air-valve; Fig. 7 is a plan view of the dash-pot piston; and Fig. 8 is a plan view of the dash-pot piston-washer.

Our carburetor has a main body 1 and a float bowl 2. Air may enter the carburetor in two ways. It may enter (Fig. 1) through the fixed-air passageway, made up of an inlet 3, a passageway 4 (Fig. 3), and a venturi 5, picking up and atomizing the gasoline at the end of a gasoline jet or nozzle 6 (Fig. 3); and, when this passageway is not large enough, by a variable auxiliary-air passageway 8 (Fig. 2) having at its entrance a spring-seated air-valve 7 which will be depressed to allow such air to enter through the auxiliary-air passageway 8 as is required. In either case, the air passes through the body of the carburetor past a throttle 9 and out through a mixture-discharge opening 10.

The gasoline enters the float bowl 2 through

a strainer cap 11 and past a float-needle 12, and the gasoline level is regulated by a float 13 operating said float-needle. From the float-bowl, the gasoline is drawn through the 5 passageway 14 (Fig. 3), past a tapered needle or fuel-valve 15, and is controlled at the circular orifice formed between the top of the passageway 14 and the fuel-valve 15. It then passes through a cross-drilled hole 17 and the 10 gasoline-nozzle 6 into the air stream in the throat of the venturi 5, and thence on through the carburetor with the air. The fuel-valve 15 has a short cylindrical section 18 by which it is guided into the orifice; and, as shown, 15 has a considerable clearance in its guide above such cylindrical section, so that it is unnecessary that it be free from lateral swinging.

As the rate of flow of air through the carburetor is changed, the air and gasoline must 20 be kept in the proper proportions. This is done by having an air-valve controlling the amount of air entering the carburetor, a fuel-valve controlling the fuel, and a proportioning-lever transmitting to the fuel-valve a 25 definite portion of the motion of the air-valve, so that as the air-flow increases, the fuel also increases in the proper proportion. The details of this construction are as follows: To the auxiliary-air-valve 7 is fixed an 30 arm 19 (Fig. 2) which is pivoted to one end of a proportioning-lever 20. This proportioning-lever passes through and has a close sliding fit in a supporting trunnion-block 21, which in turn is pivotally mounted on a fulcrum-pin 22 in the lower end of a pivotally 35 adjustable fulcrum-arm 23. On the other end of the proportioning-lever is another trunnion-block 21^a, which is pivotally attached to the top of the fuel-valve 15 (Fig. 40 3), by a pin 24. Thus as the air-valve 7 moves, the proportioning-lever turns about the pin 22 and gives to the fuel-valve 15 a motion that is in proportion to that of the air-valve; and the proportioning-lever slides 45 slightly in the trunnion-block 21 as required in this movement.

The suction causing the air to flow past the air-valve and the suction causing the fuel to flow past the fuel-valve bear substantially 50 the same relation to each other at all rates of flow of the air through the carburetor. The flow of air and the flow of fuel follow, fundamentally, the same law of increase with an increase in suction, and the lift of 55 the fuel-valve is in direct proportion to the air-valve motion. Thus the ratio of fuel to air might be expected to remain substantially constant with a straight-tapered fuel-valve and a straight-tapered auxiliary-air passage 60 way. These laws are not accurately followed, however, and to maintain a constant mixture-ratio; or to obtain any desired variation in this mixture-ratio with a change in the rate of air-flow, it is usually necessary 65 to vary from a straight taper the shape of

either the fuel-valve or the auxiliary-air passageway. We usually change the latter, as it is so much larger and therefore so much less sensitive to small changes; and use a straight-tapered fuel-valve.

The method of procedure in working out the proper shape for the inner surface of the auxiliary-air passageway is as follows: Tests are run at a large number of different rates of flow of air through the carburetor, and a record made of the weight of air and of fuel that passed during each test. From these figures the richness of the fuel to air mixture are computed for each rate of air flow. Suppose now that the mixture is found to be too rich at some particular position of the air-valve. The inner surface 25 of the auxiliary-air passageway is then hollowed out at this point until the mixture is brought to the required proportions. By this means the richness of mixture obtained at each and every flow-rate is brought to the desired point and the carburetor is made to follow the requirements of the engine with great accuracy.

The taper of the fuel-valve 15 is chosen to give the desired mixture when the fulcrum-arm 23 is substantially at right angles with the proportioning-lever 20 when the auxiliary-air valve is closed, so that a small motion of the trunnion-block 21 in either direction will not materially change the position of the fuel-valve 15 and thus affect the idle adjustment. Shifting the trunnion-block 21 toward the air-valve will cause the fuel-valve to move farther for a given air-valve motion and result in an enriched mixture at all rates of air-flow.

In order to provide a wide range of flow-rate capacities, the fixed-air opening through the venturi 5 is made small, and the auxiliary air-valve 7 is made large.

The seating spring 26 of the air-valve 7 is made strong enough so that during operation the vacuum in the body of the carburetor will be sufficient to atomize the fuel at the throat of the venturi 5, even at very low rates of air-flow.

The low-speed adjustment is made as follows: The fuel-valve 15 (Fig. 3) has its seat in a sleeve 57, which in turn is mounted in a threaded hole 58 in the body casting. This sleeve 57 has at its upper end a gear 59 (Fig. 2), which meshes with a worm 60 on the idle adjusting screw 61 (Fig. 3). Turning the screw 61 will therefore screw the sleeve 57 up or down in the threads 58, thus raising or lowering the seat for the fuel-valve 15, and making the idle mixture leaner or richer, respectively.

The enriched mixture for full power at open throttle is obtained as follows: The fulcrum-arm 23 which supports the fulcrum-pin 22 is fastened to the fulcrum-arm-shaft 49. This shaft 49 passes through the body-

casting to the outside. Arms 50 and 51 (Fig. 4) are fastened to this shaft 49 on its outer end. The arm 51 is held against an adjusting-screw 52 in a lug 53 by a spring 54 (Fig. 5 3). The position of the screw 52 affects the position of the fulcrum-pin 22, and controls the richness of the mixture throughout the range of the carburetor at partly closed throttle positions. The arm 50 is acted on by 10 a cam 55 on the throttle-shaft 56, in such a way that when the throttle 9 is wide open the lever 50 is depressed, the trunnion-block 21 and fulcrum-pin 22 are moved toward the air-valve, and in consequence the fuel-valve is 15 given a greater lift for a given air-valve motion, and the mixture is made richer.

To obtain the rich mixture for starting a cold engine, a dash adjustment is provided which connects to the lever 50 through a wire 20 62 (Fig. 4). Pulling down on the wire 62 will turn the fulcrum-arm 23 to shift the trunnion-block 21 and fulcrum-pin 22 toward the air-valve 7 to increase the lift of the fuel-valve 15 to a given opening of the 25 air-valve, and even to cause a considerable lift of such fuel-valve while the air-valve 7 is on its seat, which results effectively in an enriched starting mixture, as desired.

A dash-pot 27 (Fig. 5) serves to keep the 30 air-valve from fluttering. The dash-pot cylinder 27 lies below the fuel level of the float-chamber 2 and is always filled with fuel. The dash-pot piston 28 is a good fit in the cylinder 27, and is accordingly capable of exerting a very strong damping effect on the fluctuations of the air-valve 7.

It is desirable to have the dash-pot offer less resistance to a closing than to an opening motion of the air-valve. This is accomplished by means of a disc-check-valve. The thin disc 29 lies on a shoulder on the nut 30. This shoulder lies below the end-face of the nut 30, by a distance slightly greater than the thickness of the disc 29. The nut 30 45 screws up firmly against the drilled disc 31 (shown also in Fig. 8). The disc 29 is therefore free to drop below the lower face of the disc 31 when the piston is rising, thus allowing fuel to flow through holes 32 in the disc 31, and giving the piston a comparatively free motion. When the piston tends to descend, however, disc 29 will rise and close holes 32, thus further retarding the motion of the dash-pot piston.

55 It has already been pointed out that dash-pots as previously constructed, when effective in damping out all fluttering of the air-valve, will be too sluggish in their action when a vigorous acceleration is desired immediately after coasting. This dash-pot obviates this difficulty. The dash-pot piston 28 is slidably mounted on the valve-stem 16, but is held against the disc 31 by a spring 33. The fluctuations in the suction of the engine tending to cause the air-valve 7 to flutter when

the throttle-valve 9 is wide open, are small in magnitude. The spring 33 is strong enough to resist them completely and force the piston 28 to remain firmly in place and act like a solidly mounted piston, damping out all fluttering of the air-valve. When the car is coasting, however, the vacuum in the intake manifold is very high. When the throttle is kicked open under these conditions, this high suction is transferred to the air-valve 7, causing a very strong pull in the opening direction. Under these conditions the spring 33 collapses as shown in Fig. 6 allowing the piston 28 and disc 31 to separate, and the air-valve 7 drops immediately, just as though the dash-pot were not there.

The piston 28 is free to turn on the valve-stem 16, while the disc 31 is not. It is necessary that at least one of the holes in the piston 28 register with a hole in the disc 31. The disc 31 is therefore drilled with one fewer holes than is the piston 28, so that this result is accomplished no matter what the position of the piston.

The improved accelerating device is shown 90 in Fig. 3. It is made as a fuel-lifting mechanism as distinguished from a pump. This distinction is an important point in the operation of the device, and will therefore be brought out clearly as the detailed description of the apparatus proceeds. This fuel-lift is preferably actuated from the throttle-shaft. In the form here shown, the lift-cylinder 34 is supported on a lug 35 on the carburetor body 1, by means of a threaded 95 part 36. This lift-cylinder extends down into the fuel-chamber 2. The lift-piston 37 is fastened to the end of a piston-rod 38. The piston is drilled to provide holes 39. A thin check-disc 40 lies on top of the piston, and can move up to a shoulder 41 on the piston-rod. The fuel can therefore fill the lower end of the lift-chamber, the part 42 or lift-chamber proper, through the holes 39.

A reduced section of the lift-chamber, the 100 part or passageway 43, extends from just below the fuel level in the float-chamber 2, to some point sufficiently above such fuel level so that tipping the carburetor will never submerge its upper end in practice. This 105 section is reduced in size in order to reduce the volume of fuel required to raise the level up to the height of a cross-passage 45, thus reducing the amount the piston 37 will have to move before beginning to deliver fuel 110 through said cross-passage 45; but it is not sufficiently restricted to interfere with the free delivery of fuel through it in either direction. When the lift-piston is raised, the fuel can therefore flow freely through the 115 reduced section 43 into an upper enlarged section 44 or measuring chamber of the lift-chamber. From here it can flow through the cross-passage 45 into the venturi 5. The rate at which the extra fuel is delivered to the 120

125 130

venturi will be determined by the size of a hole 46 in such cross-passage. A ring 47 has a loose fit on the piston-rod in the upper section 44 of the lift-chamber, and serves to keep the fuel from being ejected through a cap 36 when the lift is being used vigorously. This ring 47 is in no wise a check-valve.

When accelerating from a low speed it requires only a few degrees of throttle motion to throw the engine into a full-torque condition, making a full charge of extra gasoline necessary. When the throttle is opened wide, no more fuel than this is needed. This situation is met as follows: The lower section 42 of the lift-chamber is made quite large, while the elevated section 44 is much smaller, and is provided with a large overflow passageway 48. It is therefore possible to fill the upper section 44 with a small movement of the throttle, and any fuel pumped into such upper section 44 beyond the required amount will pass through the overflow passageway 48 back into the fuel-chamber again. The total quantity of extra fuel supplied is therefore measured in this small elevated chamber-section 44, and this quantity may be determined by the height the overflow 48 is given when the carburetor is built. By this means it is possible to supply the full charge of extra fuel for acceleration with a small opening movement of the throttle without wasting fuel or causing the engine to load when the throttle is kicked wide open.

The difference between our lift apparatus and a pump lies in the fact that we have only a single check-valve and have a fuel lift-chamber that is in continuous free communication from the lift-piston to the overflow passageway 48, while a pump has two valves and two fuel chambers. In our apparatus a rapid raising and lowering of the lift-piston will merely raise and lower the same fuel in the lift-chamber, resulting in a very small delivery of fuel from the top. In a pump, however, each stroke of the piston will deliver a definite volume of fuel. In an accelerating device this will result in the following difference in performance: When the throttle is opened wide and then quickly closed with a "pump" accelerating device attached, the full charge of extra fuel for acceleration will nevertheless be added, and will be added at a time when it is not only not needed, but when the engine is already predisposed to load due to the fact that it is decelerating. In our lift device this is not the case, as the extra fuel raised on opening the throttle is immediately withdrawn when the throttle is closed. Furthermore, repeated opening and closing of the throttle attached to a "pump" will deliver an excessive amount of fuel and "load" the engine while such a result will never occur with our apparatus.

Our accelerating device is capable of wide variation from the preferred form shown,

For instance, in its preferred form it is mechanically operated in unison with the throttle, but this is not necessary to the carrying out of the essential idea of our invention. It is furthermore not essential that the accelerating device be an integral part of the carburetor, nor that the fuel be delivered on the up-stroke of the lift-piston, and these features are shown as illustrative.

We claim as our invention:

1. In a carburetor, the combination with a suction-actuated air-valve, of a dash-pot for damping the motion of said air-valve and made up of a dash-pot chamber, a piston-rod, a piston slidably mounted on said piston rod, a stop at the end of said piston-rod, and a spring pressing said piston against said stop. 75
2. In a carburetor, the combination with a suction-actuated air-valve, and an air-valve stem; of a dash-pot for damping the motion of said air-valve and made up of a dash-pot chamber, a dash-pot piston having a sliding fit in said dash-pot chamber and slidably mounted on said air-valve stem, a stop at the piston end of said air-valve stem, and a spring pressing said piston against said stop. 85
3. In a carburetor, the combination with an air-valve, a fuel dash-pot for damping the motion of said air-valve and consisting in a dash-pot chamber so located as to be filled with fuel, a dash-pot piston-rod, a dash-pot piston having a sliding fit in said dash-pot chamber and slidably mounted on said piston-rod, a stop at the end of said piston-rod and a spring pressing said piston against said stop. 95
4. In a carburetor, the combination of a suction-actuated air-valve; and a dash-pot for damping the motion of said air-valve and consisting in a dash-pot chamber, a piston yieldingly connected to said air-valve, and means enabling said piston to act as a solidly mounted piston under slight impulses but to give way readily under a heavy impulse. 105
5. In a carburetor, the combination of a suction-actuated air-valve; and a dash-pot for damping the motion of said air-valve and consisting in a dash-pot chamber, a piston yieldingly connected to said air-valve, means enabling said piston to act as a solidly mounted piston under slight impulses but to give way readily under a heavy impulse, and means for allowing said piston to move more freely in one direction than in the other. 115
6. In a carburetor, the combination of a suction-actuated air-valve; and a dash-pot for damping the motion of said air-valve and consisting in a dash-pot chamber, a piston yieldingly connected to said air-valve, means enabling said piston to act as a solidly mounted piston under slight impulses but to give way readily under a heavy impulse, and means for allowing said piston to move 125

more freely in one direction than in the other, said last named means being a check-valve arranged to open as said air-valve closes but to close automatically as said air-valve is opening.

5. In a carburetor, the combination with a mixing-chamber having an air-inlet opening, a throttle, a fuel-supply chamber, an air-valve tending to close said opening, and a fuel-valve; of means for damping the motion of said air-valve consisting in a dash-pot mechanism yieldingly connected to the air valve and capable of resisting small impulses but giving way disproportionately quickly under strong impulses.

10. In a carburetor, the combination of an air valve subjected to a variable tendency to be moved, and a dash pot connected to said air valve for normally damping the movement thereof, said connection including means normally maintaining a fixed relationship between the air valve and dash pot, but being yieldable to permit the air valve to move with relatively decreased dash pot

20 retardation upon the occurrence of a predetermined tendency to move the air valve.

8. In a carburetor, the combination of a suction actuated air valve and a dash pot connected to said air valve for normally damping the movements thereof, the connection between said air valve and said dash pot being normally rigid but including means yielding at a predetermined pressure to permit the air valve to move with relatively decreased dash pot retardation upon the occurrence of a predetermined pressure acting to move the air valve.

10. In a carburetor, the combination with a mixing chamber having an air-inlet opening, a throttle, a fuel-supply chamber, an air-valve tending to close said opening, and a fuel-valve; of means for transmitting a portion of the motion of said air-valve to said fuel-valve, and means for damping the motion of said air valve and the resultant motion of the fuel-valve consisting in a dash-pot mechanism yieldingly connected to the air valve and capable of resisting small impulses but giving way disproportionately quickly under strong impulses.

11. In a carburetor, the combination of a fuel-valve, and a dash-pot for damping the motion of said fuel-valve, said dash-pot including a piston yieldingly mounted relative to the fuel valve and arranged to act as a solidly mounted piston upon slight impulses but to give way readily under heavy impulses.

60. In witness whereof, we have hereunto set our hands at Indianapolis, Indiana, this 12th day of May, A. D. one thousand nine hundred and twenty three.

68 OTTO CARTER BERRY.
HOWARD W. LINKERT.
